UNITED STATES PATENT OFFICE.

JOHN T. H. PAUL, OF CHICAGO, ILLINOIS, ASSIGNOR TO E. GOLDMAN & CO., INC., OF CHICAGO, ILLINOIS, A CORPORATION OF ILLINOIS.

BOTTLE-WASHING MACHINE.

1,077,636.

Specification of Letters Patent.

Patented Nov. 4, 1913.

Application filed May 18, 1911. Serial No. 628,037.

To all whom it may concern:

Be it known that I, JOHN T. H. PAUL, a citizen of the United States, residing at Chicago, in the county of Cook and State of Illinois, have invented a new and useful Improvement in Bottle-Washing Machines, of which the following is a specification.

The object of the present invention is to improve, in matters of detail, the bottle-washing machine which forms the subject of my pending application for Letters Patent, Serial No. 579,470, filed August 29, 1910, to the end of increasing the efficiency of that machine.

In the accompanying drawings, Figure 1 is a view, in the nature of a diagram, of the apparatus in side elevation presenting one side thereof; Fig. 2 is a view in elevation of the opposite side; Fig. 3 is an enlarged section approximately on line 3, Fig. 1; Fig. 4 is an enlarged broken view showing a strainer device in section; Fig. 5 is a sectional view through the strainer on line 5, Fig. 4; Fig. 6 is a transverse section through the shield-equipped pipe for spraying the label-removing screens; Fig. 7 is a broken plan view of a set of the bottle-spraying pipes on their support showing means on their distal ends for relatively adjusting them; Fig. 8 is a broken view showing an enlarged plan section through the adjusting means on the opposite end of the set of spraying-pipes; Fig. 9 is an enlarged section on line 9, Fig. 7; Fig. 10 is an enlarged section on line 10, Fig. 9; Fig. 11 is a broken plan view, with the hood, spraying-pipes and shielding-plates removed, showing two of the three sectional label-removing screens and attendant mechanism; Fig. 12 is a face view of the large loose gear-wheel through the medium of which the endless-chain bottle-carrier is intermittently driven; Fig. 13 is an enlarged inner-face view of the socket-containing crank-arm which forms one member of a device for adjusting the carrier-chains to compensate for stretching thereof and correct resultant imperfect registration of the bottles with the spray-pipe nozzles; Fig. 14 is a section on line 14, Fig. 12, showing the entire adjusting device, and Fig. 15 is an enlarged broken plan view showing the manner of connecting a sectional label-removing screen with its endless actuating-chains.

Aside from the features hereinafter de-

scribed constituting my present improvements, the construction of the machine is substantially the same as set forth in my said former application, and may therefore be generally described as follows:

60

The tank for containing the supply of cleansing water is supported on a suitable frame and is shown to be formed of a series of four compartments separated by spaces 16, formed by partitions for carrying off 65 the overflow through depending pipes 17 discharging through a pipe 18 to a sewer. The washing-water in three of the compartments is kept at desired different temperatures by the admission of steam into them 70 controlled by suitable thermostatic mechanism represented as a whole at 19 in Fig. 2, as is common practice in machines of the present and analogous classes; and for filling and emptying the compartments, valved 75 pipes 20 depend from their bottoms and are connected with a horizontal pipe 21 equipped with an inlet-controlling valve 22 for the supply and a discharge-controlling valve 23. A hood 24 extends lengthwise 80 over the tank; and a track is provided above and below the tank for the travel upon it of a conveyer comprising a pair of endless chains, indicated at 25, on sprockets 26 and connected at intervals by sets of transverse 85 series of holders, indicated in Fig. 3, for supporting bottles to be washed in inverted position. For circulating the water from the tank back into it by discharging the water upwardly through jet-pipes at the 90 compartments, a motor 27 is provided having its shaft 28 common to four centrifugal pumps 29 taking their supply from the lower parts of the respective compartments through pipes 30 and returning it thereto 95 through upright pipes 31. The upper end of each pipe 31 is connected at 32 (Fig. 7) with a manifold 33, that adjacent to the last tank-compartment containing the clear or hydrant water for finally rinsing the 100 bottles, being provided with a partition 34 (Fig. 8) forming in one end of the manifold a chamber to which a supply-pipe 34¹ leads from a supply (not shown) of hydrant-water. From each manifold extend in 105 parallel relation to each other across a compartment, pipes 35 forming a set with longitudinal series of jets projecting upwardly from them, the pipes being supported on a frame 36 surmounting the respective com- 110

partment; and the manifold is formed of sections coupled together in a manner to render them relatively adjustable and render the manifold extensible and contractible for spreading farther apart or bringing closer together the jet-pipes to set or re-set them for proper registration therewith of the bottles intermittently carried by the endless-conveyer.

It is found in practice that the distal ends of the jet-pipes also require positive adjustment each time their opposite ends are adjusted by manipulating the couplings of a manifold 33; and means hereinafter described for that purpose from one of the present improvements, illustrated in detail in Fig. 9: The closed ends of these pipes, which are supported on a frame 36, carry similar heads 37 provided with transverse alining openings in their upper ends forming bearings for a shaft 38, which is rotatably confined in an intermediate head by collars 39, 39 embracing it, adjacent to one of which the shaft carries a hexagonal flange 40 for the application of a wrench. Where the shafts works in the heads immediately flanking the one in which it is thus confined, it is provided with similar relatively-fine screw-threads 41 engaging like threads in the bearings; the second-removed threaded sections 42 of the shaft are alike and relatively coarser, to engage like threads in the respective bearings; and the end-section of the shaft is provided with a still coarser thread 43 to engage a like thread in its bearings. The relations of the different threads are such that when, by turning the shaft, the threads 41 shift the heads 37 containing them and the ends of the respective jet-pipes a certain distance toward or from each other, depending on the direction of turning, the threads 42 will correspondingly shift the heads and pipes they control twice that distance and the thread 43 will similarly shift the head and pipe controlled by it twice the distance of the heads actuated by the threads 42, thereby to maintain the same relation between those ends of the pipes in each adjustment thereof, which is made to correspond with each adjustment of the sectional manifold 33.

The conveyer 25 is actuated intermittently by a shaft 44 (Figs. 1 and 11) carrying on one end a worm-wheel 45, with which meshes a worm 46 carrying a relatively-large gear-wheel 47 on one end and a smaller gear-wheel 48 on its opposite end, to mesh, respectively, with a relatively-small pinion 49 and a larger pinion 50 spaced apart on a shaft 51, which is suitably journaled in bearings on the tank and connected at a pulley 52 on one end by a belt 53 with a pulley 54 on the motor-shaft 28, which thus drives the worm 46. The pinions 49 and 50 are shiftably supported on the shaft 51 and

are respectively engaged by fingers 55 and 56 extending from a rod 57 supported in bearings to adapt it to be moved longitudinally through the medium of hand-lever 58 to vary the speed of the conveyer. The shaft 44 also carries, adjacent to the worm-wheel, the stud-member of a Geneva-drive 59, the star-wheel member of which is journaled on a stub-shaft 60 carrying a pinion 61 to mesh with a gear-wheel 62, which is loosely mounted on a shaft 63 that carries a pair of the sprockets 26 for actuating the chains of the conveyer 25. From a spoke of this gear-wheel extends outwardly a finger 64 forming one member of a chain-adjusting device (Figs. 13 and 14), the other member of which is a crank-arm 65 keyed at its hub to the shaft and provided with a socket-section 66, into which the finger projects between set-screws 67 working in the opposite sides of the socket-section.

In the event of the chains of the conveyer 25 stretching under the strains to which it is subjected, or of shortening thereof, the intermittent movements of the conveyer by the action of the Geneva gear will fail to register the sets of inverted bottles, in their holders connecting the chains, properly with the jets of the series of sets of jet-pipes below the upper portion of the conveyer path. Any inaccuracy in this regard may be readily corrected, without interrupting the operation of the machine, by loosening one of the set-screws 67 and turning the other against the finger 64 to suitably turn the wheel 62 and thereby shift the conveyer-chains forward or backward to the extent required for effecting required accuracy in the registration.

As in the machine of my aforesaid pending application, endless screen-conveyers 68 are provided to extend transversely across different compartments of the tank underneath the sets of jet-pipes therein to catch and carry off the labels and dirt washed from the bottles. Such conveyers are provided in three successive compartments of the present machine, but are shorter than the former ones and of different construction; and they are arranged to work through openings 69 in the sides of the three tank-compartments presented in Fig. 2 and are covered by a downwardly-inclined chute 70 on the tank-side and through which these conveyers discharge the matter they intercept out of the machine. A drive-shaft 71 (Fig. 11), shown to be formed of coupled longitudinal sections, is journaled in bearings to extend in the chute transversely thereof and is geared at its outer end to the shaft 44, the gear 72 on which meshes with a pinion 73. Each conveyer 68 consists of a frame formed of a pair of similar side-arms 74 provided with feet 75, at which they are rigidly secured upon a ledge 76 pro-

vided in the chute to cause the arms to incline slightly in a downward direction from the chute through an opening 69 into the tank. The outer end of each side-arm is 5 formed with a head 77, through which the shaft 71 passes, and it is provided with a longitudinal slot 78 in its inner end, in which works a set-screw 79 for the purpose hereinafter explained. The shaft 71 carries, loosely, adjacent to the inner side of 10 each arm 74, a sprocket 80 confined between collars on the shaft; and in the slotted ends of each pair of the arms is non-rotatably supported at its ends a shaft 81, in which a set-screw 79 works and which carries near 15 its ends, loosely confined upon it between collars, sprockets 80 like those on the shaft 71 and forming pairs therewith. Endless chains (Fig. 15) 82 extend about the pairs 20 of sprockets, and alternate links of the chains are provided with inwardly-projecting tongues 83. The screen for each conveyer is sectional, being formed of a series 25 of rectangular frames 84 covered with wire-screening 85, and each section is riveted through opposite ends of its frame to opposite tongues 83 on the pair of conveyer-chains; and the section merely rests on the next succeeding pair of tongues. 30 The described construction of the conveyers 68 greatly increases their effectiveness and facilitates repairing them, since wear on any part of the screen that would otherwise render the entire conveyer useless merely requires the removal of the worn section and its replacement by a whole one. If the chains 82 require adjustment this may be effected by properly turning the set-screws 79 to move the shafts 81. 35 In the operation of the machine by the driving action of the motor 27, all as set forth in my said former application, the gear-connections with the motor-shaft of the shafts 44 and 71 continuously drive the 40 conveyers 68 while intermittently driving the conveyer 25 equipped with the bottle-holders. Labels and dirt washed from the bottles fall upon a pair of oppositely-inclined tables 86 and 87 (Fig. 3) supported 45 to extend below and across the bottle-conveyer above the compartments equipped with conveyers 68, and overlap each other over the receiving ends of the screen-conveyers to there discharge thereon. A spray-pipe 88 provided with deflecting shields 89 50 is supported in the chute 70 to extend lengthwise of the outer ends of the conveyers 68, whereby in turning their sectional screens, the undermost sections at their 55 outer ends, as represented in Fig. 3, before being turned about the shaft 71, are presented bottom upward to the spray from the pipe 88, which is directed against them in a sheet by the deflectors 89 and keeps the 60 screens clean. The washing-water for this 65

purpose comes from the manifold connection at 32 (Fig. 7) of the last tank-compartment through a branch 32¹ connected with the pipe 89, which contains a regulating-valve 90 at the junction. The hydrant-water which performs the final rinsing runs 70 into this last compartment, and instead of overflowing thence immediately into the sewer and being wasted, the apparatus is so arranged that the respective pump utilizes 75 just about that quantity for thus cleaning the screens, thereby effecting a material saving in water, the hydrant-water being caused to perform the two functions of rinsing the bottles and thereafter washing the 80 screens.

To intercept foreign matter in the water passed through the pumps against reaching and clogging the nozzles of the spray-pipes 35, a peculiar construction of strainer 91 85 (Figs. 3, 4 and 5) is interposed in each discharge-pipe 31 leading from a pump. This strainer is constructed to adapt it to be readily taken apart for cleaning it and as readily put together. It comprises a cylindrical chamber 92 closed by a cap 93 on its outer end, with a curved passage 94 extending upwardly from its opposite end and terminating in a nipple 94¹ for connection with the pipe 31, a similar lower nipple 95 being 90 also provided for a like purpose. In the chamber 92 is seated, at the inner end of the latter and in the cap 93, a tubular screen 96. The washing-water from a pump fills the chamber 92 surrounding the screen and flows 100 through the latter, relieved of its contained foreign matter, on its way to a header 33.

Minor features of the machine that may be mentioned, since they are illustrated, are covered ports at 97 on one side of the tank 105 through which to introduce the chemical for producing a suitable solution of the washing water; windows 98 on opposite sides of the tank-compartments, through which to inspect the working of the interior mechanisms, and windows on the outer side of the chute, one of which is indicated at 99 on Fig. 3 as being supported by a hinge-connection at 100 with the top of the chute. 110

I reserve the right to claim, in future applications for Letters Patent, the inventions herein shown and described relating to the adjustment of the jet-pipes relative to each other, to the screen-conveyer construction for catching and removing labels and dirt 115 washed from the bottles, and to the setting device for the endless chain-conveyer. 120

What I claim as new and desire to secure by Letters Patent is—

1. In a bottle-washing machine, the combination of a tank, a track, a bottle-conveyer supported on the track to travel over the tank, a set of jet-pipes comprising a manifold divided into washing and rinsing water-chambers and having jet-pipes project- 125 130

- 4
- ing from it, means for supplying washing-water to one manifold-chamber, means for supplying rinsing water to the other manifold-chamber, a screen-conveyer working in the tank below said pipes, and a spraying-pipe supported to discharge against the screen-conveyer and having a supply-pipe connecting it with said washing-water supplying-means.
- 10 2. In a bottle-washing machine, the combination of a tank, a track, a bottle-conveyer supported on the track to travel over the tank, a set of jet-pipes supported to extend below the track, means for supplying washing-water to said pipes, a screen-conveyer working in the tank below said pipes, and a pair of tables inclining downwardly toward each other in the tank below said pipes and lapping one another to discharge at the receiving end of the screen-conveyer.
- 15 3. In a bottle-washing machine, the combination of a tank containing a side-opening, a track, a bottle-conveyer supported on the track to travel over the tank, a set of jet-pipes supported to extend below the track, means for supplying washing-water to said pipes, a discharge-chute on the tank at said opening, and a screen-conveyer working through said opening below the pipes to catch labels and dirt washed from the bottles and discharge the same into said chute.
- 20 4. In a bottle-washing machine, the combination of a tank containing a side-opening, a track, a bottle-conveyer supported on the track to travel over the tank, a set of jet-pipes supported to extend below the track, means for supplying washing-water to said pipes, a discharge-chute on the tank at said opening, a screen-conveyer working through said opening to catch labels and dirt washed from the bottles and discharge the same into said chute, and a shield-equipped spray-pipe supported in the chute to discharge against the screen-conveyer.
